CLAIM

The ornamental design for an exhaust gas purifier with function to improve fuel consumption, as shown and described.

DESCRIPTION

1. Exhaust gas purifier with function to improve fuel consumption

2. Exhaust gas purifier with function to improve fuel consumption

1.1 : Front

1.2 : Top

1.3 : Right

1.4 : Left

1.5 : Cross-sectional view taken along line B-B in view 1.1

1.6 : Cross-sectional view taken along line A-A in view 1.4

2.1 : Front

2.2 : Top

2.3 : Right

2.4 : Left

2.5 : Cross-sectional view taken along line B-B in view 2.1

2.6 : Cross-sectional view taken along line A-A in view 2.4

Air purification devices that can be attached to the exhaust pipe of a car to clean exhaust gases; the thin lines represent the solid shape of the designs; the hatching represents the cross-sectional shape of the designs; the bottom views are omitted because they are symmetrical with the top views; the back views are omitted because they are symmetrical with the front views.
